(57) **CLAIM**

The ornamental design for a remote control for multimedia controller, as shown and described.

DESCRIPTION

FIG. 1 is a top plan view of a remote control for multimedia controller showing our new design;

FIG. 2 is a right side elevational view thereof, the left side being a mirror image of the right side;

FIG. 3 is a front elevational view thereof;

FIG. 4 is a rear elevational view thereof; and,

FIG. 5 is a bottom view thereof.

The portions of the remote control shown in broken lines form no part of the claimed design.
